UNITED STATES PATENT OFFICE.

JOHN F. MURPHY, OF MINNEAPOLIS, MINNESOTA, ASSIGNOR TO FLOUR CITY ORNAMENTAL IRON WORKS, OF MINNEAPOLIS, MINNESOTA, A CORPORATION OF MINNESOTA.

DESIGN FOR A STREET-LAMP.

41,438.

Specification for Design.

Patented June 6, 1911.

Application filed April 25, 1911. Serial No. 623,323. Term of patent 7 years.

To all whom it may concern:

Be it known that I, JOHN F. MURPHY, citizen of the United States, residing at Minneapolis, in the county of Hennepin, State of Minnesota, have invented a new, original, and ornamental Design for Street-Lamps, of which the following is a specification, reference being had to the accompanying drawing, forming part thereof.

The figure is a perspective view of a street lamp, showing a new design.

I claim:

The ornamental design for a street lamp, as shown.

JOHN F. MURPHY.

In presence of—

WM. BURNS,
CHAS. N. GRAMLING.
